APPARATUS FOR TREATING FABRICS

Raymond C. Benner, Henry P. Kirchner, and Romie L. Melton, Niagara Falls, N. Y., assignors to The Carborundum Company, Niagara Falls, N. Y., a corporation of Pennsylvania

Application December 5, 1932, Serial No. 645,760

2 Claims. (Cl. 26—31)

This application relates to methods and apparatus for surfacing cloth whereby a hard and more or less smooth surface is converted into a fleecy surface. One such product is that ordinarily called cotton flannel.

One object of the invention is to provide rolls with particularly efficient working surfaces for use in altering the smooth hard character which is ordinarily found in cotton cloth, so that the 10 treated cotton cloth will approach more closely to woolen cloth in its general appearance and feel. In other words, one object of this invention is to so process cotton cloth that its surface is given a matted effect whereby it entraps air which gives 15 it a lower heat conductivity. The utility of such rolls, of course, is not confined because it is effective also with other fabrics, e. g. woolen goods.

The differences that exist between cotton and woolen cloth of the same thickness (even when 20 woven in a similar manner) are due primarily to differences in the character of the woolen and cotton fibers. Wool fibers have a complex physical structure comprising an internal column of cellular marrow, an intermediate layer of cortical 25 tissue that gives the fiber its quality of rigidity and resistance to crushing strain. The wool fiber is naturally kinked and when a group of wool fibers are brought together they form a matted body that entraps air with the consequence that 30 the woolen body is a poor conductor of heat.

The cotton fiber on the other hand, consists of a single long tubular cell without kinks, which is attached directly to the surface of the seed. On ripening the cell collapses and forms a ribbon-like fiber twisted into a screw-like band, the number of twists ranging from 150 to 300 twists per inch. The physical characteristics of wool and cotton fibers can be somewhat altered by sizing, that is by loading up the yarn with starch, fats, 40 waxes, etc. This process is especially beneficial in improving the cotton fiber which is naturally deficient in strength. The sizing strengthens cotton yarn and protects it from abrasive forces such as occur during the process of weaving. 45 During this process the warp threads are subjected to a fairly heavy tension and are subjected to abrasion from the reciprocating members which are moved back and forth between the warp threads. The size in woven cotton cloth 50 gives it a smooth finish appearance which is generally appreciated in cotton goods. In woolen goods however (or in goods designed to resemble woolen goods in their surface finish) a soft fleecy surface is desired and the fibers preferably do 55 not present a smooth appearance. While woolen

warps are sized to offset the difficulties of weaving, this size is usually washed out of the wool again so that it will retain its soft, wooly feel. In the case of cotton, the washing out of the sizing material would greatly diminish the weight 5 of the cloth and the strength of the fibers.

An understanding of the present invention can be obtained by referring to the accompanying drawing in which:

Figure 1 represents a sectional elevation of a 10 roughing cylinder with a surface covering of granular particles;

Figure 2 is an enlarged fragmentary view illustrating a piece of coated fabric to which granular particles are haphazardly attached; 15

Figure 3 is a similar view illustrating a granular surface of the kind used for roughing cloth according to the process disclosed in the present application.

A roughing cylinder 2 is indicated in Figure 1. This cylinder has a covering of web 3 which has a working surface of granules 4. These granules are attached in such a manner that most of them have their major axes in some other direction than parallel to the surface of the cylinder, e. g. 20 at an angle between 45° and 90° inclusive. The cylindrical surface of 2 can be provided with liquid hardenable adhesive to hold the web tightly to the cylinder or the web may be secured to the cylinder by means of suitable clamps. 25

In roughing cotton cloth, the cloth is drawn along in contact with the surface 4 of the cylinder 2 but at a different speed from the speed given to the surface 4 by the driving shaft 6. The action of the projecting granules 4, which may be at 30 an angle of from approximately 45° to 135° with the backing, is to draw out a part of the fibers from the threads and thus leave numerous loose ends of fibers which are still attached at their other ends to the threads. This process makes 35 the surface of the cotton cloth more fluffy so that it closely resembles flannel in appearance and feel. Ordinary cotton cloth, on the other hand, is rather smooth and free from nap, whereas a 40 fluffy surface entraps air and reduces the heat 45 conductivity.

The usual granular coated web, such as illustrated in Figure 2, has not been entirely satisfactory in converting a smooth hard surface of woven threads into a fleecy surface. The flat or 50 dull portions of the granules 5 engage the cloth and produce an abrading action which wears away a portion of the surface threads thereby reducing the weight and decreasing the strength 55 of the woven material. Such granular coatings

fill or clog up more easily and increase the heating, due to friction. As a result the cloth under treatment may become scorched and the ends of any loose fibers singed or burned away.

- 5 The above difficulties are eliminated with our improved oriented granular coating (shown by Figure 3) and superior results obtained by the use thereof. The sharp projecting points of the granules 4 readily penetrate the surface of the woven threads and pick or draw out the ends of the fibers without removing them entirely. The relatively large open space between the oriented granules prevents the granular coating from becoming filled or clogged. A lower pressure is required to effect a desired penetration of the granules into the surface of the cloth than is the case with the usual granular coating. Obviously less heat is generated by friction in the case of the oriented granular coating and such a web is 10 more efficient in converting a smooth hard surface of woven threads into a fleecy surface.

While the description in the specification re-

lates to apparatus for and methods of treating cotton cloth, woven materials made from other fibers may be treated in an analogous manner.

We claim:

1. Apparatus for treating cloth comprising a rotary support and a covering fastened thereto, said covering comprising a web coated with elongated abrasive particles the major proportion of which are separated from each other by a distance less than their major axes and attached 10 endwise to the surface of the web.

2. Apparatus for treating cloth comprising a rotary cylinder, a covering fastened thereto, said covering comprising a web coated with elongated abrasive particles, the major proportion of which are separated from each other by a distance less than their major axes and attached endwise to the surface of the web and means for securing said coated web to said cylinder.
